UNITED STATES PATENT OFFICE

ADRIEN DAWANS, OF BRUSSELS, BELGIUM

APPARATUS FOR MELTING FINELY DIVIDED MATERIALS

Application filed July 12, 1928, Serial No. 292,211, and in Belgium July 29, 1927.

This invention relates to apparatus for melting finely divided materials comprising a stationary inclined bed plate along which the melted materials slide by gravity.

With a view to replacing the material which has melted and flowed away, the zone of melting and flow is situated, according to the invention, at the foot of a pile of material, the angle of slope of which is the natural angle of repose of the material.

In order to prevent an agglomeration of the finely divided particles which would interfere with the flow of the molten metal, the invention provides a screen formed for example by a refractory wall by means of which the melting zone can be limited near the upper part of the hearth.

The invention further involves a particular embodiment wherein the zone in which the said material is led in a molten state may be situated in proximity to the lower end of the bed plate or may abut against the inclined surface of the pile.

Further, according to the invention, the gases of combustion may be led at a certain distance from the melting zone by means of a screen formed for example by a refractory wall. In order to permit use to be made of mechanical devices adapted to serve, in particular, for advancing the material, the two screens mentioned may produce in the hearth a zone which is at a lower temperature than that of the melting zone and which will be adapted to receive the said mechanical devices.

With a view to oxidizing in the upper part of the hearth certain oxidizable elements such as carbon, pyrites, etc., which may be contained in the said material, the invention further provides for an additional admission of air into the hearth.

The accompanying drawings illustrate by way of example and in a non-limiting manner two embodiments of the invention.

The latter extends to the various original features which the arrangements shown comprise.

Figure 1 is a perspective view with a part cut away of the device constructed for melting the said materials.

Figure 2 is a perspective view of the device with a screen.

The hearth comprises a bed plate 2a inclined at approximately 20° to the horizontal so as to discharge by gravity, over the downwardly-curved lip 2g at the end of the bed plate, the molten product which is obtained at 2f under the action of burners 3a supplied either with blast furnace gas or with pulverized coal, etc. The melting may, however, be obtained also by means of simple coal-burning hearths.

In order to effect the automatic feeding of the material to replace that which has been melted, the material to be treated, which is poured into the chute 4, descends the latter by gravity and flows out through the lower aperture 4a thereof onto bed plate 2a where it forms a pile, shown in dotted lines, whose surface 4b assumes naturally, when at rest, an inclined or sloping position known as its natural slope or angle of repose.

To vary the amount of the material supplied to the hearth and thus change the slope 4b, the aperture 4a of the chute 4 (which latter is situated in the interior of the gas-discharging chimney 5) may be closed by a movable sliding door 4k balanced by a counter-weight 4p and the position of which can be controlled from the outside by suitable means (not shown).

The melting of the material takes place at the foot of the slope 4b, and the molten metal flows along the inclined bed plate and discharges into and solidifies in vessels 2k placed at the end 2g of the said hearth.

In order to make complete use of the heat contained in the fuel, the above mentioned material, which is fed to the hearth in a direction opposite to that in which the burning gases are discharged, is heated by the latter in the chute 4 and at the upper part 4m of the slope 4b.

With the object of preventing an influx of cold air, the end or lip 2g of the hearth is partly closed by a movable wall 2t so as to leave merely a sufficient passage for the discharge of the product from the melting operation.

In the case of Fig. 2, in which the con-

struction is approximately the same as in Fig. 1, the material is led in proximity to the end or lip 2g of the said bed plate 2a where melting takes place under the action of burners

- 5 3b supplied with blast furnace gas, or with pulverized coal, etc. In this form, the melting zone is limited by means of a screen formed by a refractory wall 5a which is rigidly connected with the side walls 2p of the 10 hearth and is arranged at a short distance from the end 2g of the hearth; the screen also comprising a top wall or member 5f which overhangs the lower part of the sloping pile and directs the hot gases from the molten 15 material toward the upper part 4m of the pile where they heat the material. The two walls 5a and 5f may be integral, producing a structure of L-section.

For the purpose of reducing the depth or 20 thickness of the material at the melting point 2f, the wall 5a is caused to penetrate into the sloping surface of the pile in such a way as to produce a second natural slope 4g which has a different inclination than the first or main 25 slope.

In order to prevent too rapid solidification 30 of the molten product and the formation of chains of solidified grains of material starting from the end 2g of the bed plate, the said product, before falling into the vessels 2k in which it solidifies, passes through a sheet of 35 gas at a very high temperature obtained by arranging the burners 3b opposite and slightly below the said end 2g.

35 The gases coming from the melting pass in a conduit constituted by a refractory wall such as 5f, the side walls such as 2p, the upper wall of the hearth adjacent to the said side walls, and the incline of the material to be 40 melted represented in the drawings by dotted lines toward the top of the hearth 2 where at 4m they reheat said material.

By the arrangement of these refractory 45 walls 5a and 5f within the hearth 2, a zone 2m is produced in the hearth which is at a lower temperature than the melting zone 2f, in which zone 2m it will be possible to dispose 50 mechanical devices such as blade wheels, etc.

In order to reduce further the temperature 55 of the zone 2m, air admission tuyeres 5g (shown in dotted lines) may project into this zone above or in advance of the said wall 5a.

As a result of the addition of the amount 60 of supplementary air a certain part of the carbon contained in the material charged into chute 4 and which may be formed by blast furnace dust, is burnt at 4m. The combustion of this carbon contributes in heating the material at 4m and consequently increases the efficiency of the apparatus.

In the operation of the invention, dust 65 from blast furnaces may be treated in a hearth analogous to the one hereinbefore described, during which treatment the ferric oxide contained in this dust is transformed

into ferrous oxide under the action of the heat before the products reach the end or lip 2f in the melting zone.

What I claim is:

1. Apparatus for melting finely-divided material, comprising a chamber provided with an inclined, fixed bed plate; a vertical duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the upper inclined surface of the pile and the plane of the bed plate; and a chimney surrounding the duct for discharging the gases of combustion. 70 75 80 85

2. Apparatus for melting finely-divided material, comprising a chamber provided with an inclined, fixed bed plate; a vertical duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the inclined surface of the pile and the plane of the bed plate; means for varying the height of said aperture so as to change the position of the foot of the pile in respect to said melting means; and a chimney surrounding the duct for discharging the gases of combustion. 90 95 100 105

3. Apparatus for melting finely-divided material, comprising a chamber provided with an inclined, fixed bed plate; a vertical duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the inclined surface of the pile and the plane of the bed plate; a chimney surrounding the duct for discharging the gases of combustion; and a screen located between the melting zone and the material to be melted, and directly behind the melting zone, said screen providing an upper free space for the passage of 115 120 125 130

the gases and a lower one for the entrance of material into the melting zone.

4. Apparatus for melting finely-divided material, comprising a chamber provided with an inclined, fixed bed plate; a vertical 130

duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the inclined surface of the pile and the plane of the bed plate; a chimney surrounding the duct for discharging the gases of combustion; a screen located between the melting zone and the material to be melted, and directly behind the melting zone, said screen providing an upper free space for the passage of the gases and a lower one for the entrance of material into the melting zone; and a second screen associated with the first one to form at the upper part of the apparatus with the walls thereof a conduit through which the gases of combustion are forced to pass.

5. Apparatus for melting finely-divided material, comprising a chamber provided with an inclined, fixed bed plate; a vertical duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the inclined surface of the pile and the plane of the bed plate; a chimney surrounding the duct for discharging the gases of combustion; and an L-shaped screen, one branch of which is located between the melting zone and the material to be melted while the other branch is located in the upper part of the apparatus above the material to be melted.

6. Apparatus for melting finely-divided material, comprising a chamber provided with an inclined, fixed bed plate; a vertical duct situated at the upper end of the bed plate and through which the finely-divided material is introduced, said duct having an aperture in its bottom through which the material escapes and forms a pile extending along the bed plate and having its greatest height comprised between the upper edge of said aperture and the bed plate; melting means acting upon a definite portion of material situated at the intersection of the inclined surface of the pile and the plane of the bed plate; a chimney surrounding the duct for discharging the gases of combustion; an L-shaped screen, one branch of which is located between the melting zone and the material to be melted while the other branch is located in the upper part of the

apparatus above the material to be melted; and pipes for the admission of supplementary air provided in the parts of the lateral walls comprised in the angle of the L-shaped screen, such supplementary air serving to 70 oxidize certain elements contained in the material under treatment before it enters into the melting zone.

In testimony whereof I affix my signature.
